UNITED STATES PATENT OFFICE.

WILLIAM N. SELIG, OF CHICAGO, ILLINOIS, ASSIGNEE TO SELIG POLYSCOPE COMPANY, OF CHICAGO, ILLINOIS, A CORPORATION OF ILLINOIS.

MOVING-PICTURE PROJECTING-LANTERN.

971,864.

Specification of Letters Patent. Patented Oct. 4, 1910.

Application filed April 20, 1909. Serial No. 491,025.

To all whom it may concern:

Be it known that I, WILLIAM N. SELIG, a citizen of the United States, residing at Chicago, in the county of Cook and State 5 of Illinois, have invented certain new and useful Improvements in Moving-Picture Projecting-Lanterns, of which the following is a specification.

The present invention relates more particularly to the construction of the lantern box or casing, and to the means afforded for securing access to the electric light carbons therein contained. The carbon supporting and adjusting devices are mounted upon a 10 portion of the lantern, which is adapted to be retracted from the box or casing so that the carbons can be attended to or renewed from time to time.

The principal object of the invention is to 20 so construct its extensible portion that protection will be afforded against the falling of sparks or pieces of incandescent carbon when the carbons are drawn out into the open and away from the protection afforded 25 by the walls of the box itself.

Further objects will appear from a detailed description of the invention, which consists in the features of construction and combination of parts hereinafter described 30 and claimed.

In the drawings, Figure 1 is a longitudinal sectional view through the center of the box, showing the position occupied by the carbon adjusting mechanism when lying 35 within the interior of the box, and showing in dotted lines its position when retracted, the base portion being removed in this figure; Fig. 2 is a cross sectional view of the box, showing the mounting therefor; Fig. 40 3 is a sectional plan view of the box, taken on line 3—3 of Fig. 1, and showing the base portion in elevation; Fig. 4 is a perspective detail of one of the rod supporting brackets; Fig. 5 is a section on line 5—5 45 of Fig. 6; Fig. 6 is a side elevation of the completed lantern; and Fig. 7 is a front elevation of the completed lantern.

The lantern, as a whole, is in the form of 50 a rectangular box having side walls 5, a front wall 6, and a floor 7. The walls of the box are preferably formed of sheet metal, such as sheet iron, and the edges of the walls are secured into a rectangular

front frame 8 and a rectangular rear frame 9. The front frame comprises an open 55 framework 14 having lower flanges 10 and upper flanges 11 of angle formation, connected by side flanges 12, and the rear frame likewise comprises rails of angle formation. The front frame serves to support the usual 60 projecting head 13 and connected portions, which are secured to the framework 14.

The box further comprises a roof 15 having a center dome 16 and a superimposed perforated head 17, but these features of 65 construction form no portion of the present invention and need not be described in detail. The rear of the box is adapted to be closed by a closing wall 18, comprising a frame 18^a, having cross bars 18^b and flanges 70 18^c around the edge thereof, and further comprising a plurality of metal panels 18^d and screen panels 18^e, adapted to slip over the edges of the rear frame when the closing wall is moved to closed position. 75

Within the box, near the lower corners, are located a pair of guide tubes 20 which extend parallel with the side walls of the box and have their ends entered into the lower rails of the front and rear frames, 80 respectively, although the tubes might be otherwise supported. The rear ends of the tubes are open to receive a pair of guide rods 21, the rear ends of which rods are rigidly connected to the closing wall and serve to 85 guide the closing wall in traveling toward and from the open rear end of the box. The closing wall, furthermore, has secured thereto a pair of inner guide rods 22, the forward ends of which are entered into a cross 90 head plate 23 which embraces the guide tubes and rides thereon as the closing wall is moved back and forth. The inner rods 22, furthermore, serve as guide rods for the adjustable carbon supporting mechanism 24, 95 which is mounted upon a rider 25 slideable upon the rods 22; but in view of the fact that the carbon supporting mechanism forms no part of the present invention it is not deemed necessary to refer to it in detail. 100

The front and rear frames of the box are each provided with a pair of depending lugs 26 which are slidably mounted upon cross rods 27, which cross rods in turn are carried by transversely extending bracket 105 arms 28 provided with lugs 29 and 30. Each

of the lugs 29, which may be termed the outer lugs, receives the end of one of the cross guide rods, and each of the lugs 30 furnishes a stop for limiting the movement of the box. As shown in Fig. 2, one of each pair of lugs 26 is located on the rod 27 between the lugs 29 and 30, while the other lug 26 is located to the rear of the lug 30 in each case, the arrangement being one whereby, when the box is moved to its rearmost position, it will be unsupported, save only by the projecting portions of the rods 27, which, however, are firmly supported and anchored to afford a rigid mounting for the box. Each of the bracket frames 28 is provided, on its under side, with depending ears 31, which embrace longitudinal guide rods 32 and 33, the ends of which are entered into lugs 34 formed upon a cross bar 35 which is screwed or otherwise rigidly secured to a flat base frame 36 adapted to rest upon a table or other suitable support for the lantern. The closing wall, at the rear of the box, has secured to its lower edge a flanged tray 37, which underlies the carbon supporting mechanism 24, and, when the closing wall is in position to close the box, occupies a position beneath the floor of the box, but is adapted to be retracted with the closing wall when the latter is open. The tray, as shown in Fig. 2, rests upon the rear inner lug 30, which furnishes a support for the free end of the tray and tends to support it when the closing wall is moved back to the position shown in dotted lines. The box is further provided with a handle 38 on its side, which facilitates its longitudinal and transverse adjustments.

In use, the lantern as a whole, can be moved forward and back along the longitudinally extending rods 32 and 33, and can be adjusted transversely along the cross rods 27, which arrangement of guide rods serves to permit any desired adjustment of the box to be made in order to bring the projecting head into proper co-relation to the lines of a moving picture projecting machine or other apparatus with which the lantern is used. When it is desired to open the lantern, the closing rear wall can be thrown back to open position, retracting with it the apron, so that access can be had to the carbons and the latter removed or adjusted without danger of fire from falling sparks or pieces of carbon, which, if detached, will in the majority of cases be caught in the tray when the lantern is opened. The arrangement of guide rods and tubes is one which affords a firm and rigid mounting for the closing wall with the mechanism which moves therewith, and greatly facilitates the adjustment of the lantern.

It will be understood that the present invention is not concerned with the method 65 of forming the walls of the lantern, which

may be of single or double thickness; or with other details of construction, which are usually in lanterns of the present description.

The means for adjusting the carbon holder is as follows: A stem 39 is provided, which is connected by suitable gearing to the carbon holder for moving the ends of the carbon in and out of contact. A stem 40 is provided, which is connected by suitable gearing, to swing the carbon from side to side of the casing and properly align it with the lenses, and a stem 41 is provided which is operatively connected to gearing for raising and lowering the carbons; and, as shown in Fig. 1, all three of the stems extend through the rear wall to the outside of the casing, where they are easily accessible for manipulation by the operator.

What I regard as new and desire to secure by Letters Patent is:

1. In a projecting lantern, the combination of a box open at one end, a closing wall for the open end, guide tubes fixedly secured to and lying within the box, rods carried by the closing wall and telescoping into the guide tubes, and furnishing a slidable mounting between the box and the closing wall, and lighting devices connected to and movable with the closing wall, substantially as described. 85
2. In a projecting lantern, the combination of a box open at one end, a closing wall for the open end, guide tubes fixedly secured to and lying within the box, outer and inner rods carried by the closing wall, the inner rods telescoping into the guide rods, and furnishing a slidable mounting between the box and closing wall, lighting devices, the inner rods furnishing a mounting for the lighting devices, whereby said lighting devices are movable with the closing wall, substantially as described. 90
3. In a projecting lantern, the combination of a box open at one end, a closing wall for the open end, guide tubes fixedly secured to and lying within the box, rods carried by the closing wall and telescoping into the guide tubes, and furnishing a slidable mounting between the box and the closing wall, lighting devices connected to and movable with the closing wall, and a tray carried by the closing wall and underlying the lighting devices when the same are withdrawn from the interior of the box, substantially as described. 100
4. In a projecting lantern, the combination of a box open at one end, a closing wall for the open end, guide tubes fixedly secured to and lying within the box, outer and inner rods carried by the closing wall, the outer rods telescoping into the guide rods, a cross-head plate attached to the free ends of the inner rods and slidably mounted on the guide tubes, the crosshead plate and outer rods co-operating to form a slidable mount. 110

ing between the closing wall and box, lighting devices, the inner rods furnishing a mounting for the lighting devices, whereby said lighting devices are movable with the closing wall, substantially as described.

5. In a projecting lantern, the combination of a box, lighting devices within said box, a base frame, longitudinally extending rods fixedly secured with respect to said 10 base frame, transversely extending rods, bracket arms, downwardly projecting lugs on the bracket arms embracing longitudinally extending rods, and forming a sliding connection between said arms and rod, upwardly projecting lugs on the bracket arms 15 in which the transverse rods are secured, lugs depending from the box, embracing the transverse rods and forming a sliding connection between the box and transverse

rods, whereby transverse and longitudinal adjustment of the box with respect to the base frame is obtained, substantially as described.

6. In a projecting lantern, the combination of a box open at one end, a closing wall for the open end, fixed guide members secured in the interior of the box and extending longitudinally thereof, members carried by the closing wall, adapted to travel within said guide members, the fixed guide members and members carried by the closing wall co-operating to form a sliding connection between the closing wall and box, substantially as described.
